PORTABLE MANUALLY-OPERATED SCRAPER

Harold A. Rippel, 223 Westbridge Drive,
Berea, Ohio 44017

Filed May 3, 1966, Ser. No. 2,133

Term of patent 7 years

(Cl. D9—6)

FIG. 1 is a perspective view of a portable manually-operated scraper showing my new design;

FIG. 2 is a top plan view thereof; and

FIG. 3 is a side view thereof.

The side not shown is substantially like the side shown.
I claim:

The ornamental design for a portable manually-operated scraper, as shown and described.
